UNITED STATES PATENT OFFICE.

ROLAND RAKESTRAW, OF WYOMING, ILLINOIS.

ROTARY HARROW.

SPECIFICATION forming part of Letters Patent No. 606,300, dated June 28, 1898.

Application filed May 19, 1897. Serial No. 637,219. (No model.)

To all whom it may concern:

Be it known that I, ROLAND RAKESTRAW, a citizen of the United States, residing at Wyoming, in the county of Stark and State of Illinois, have invented certain new and useful Improvements in Rotary Harrows; and I do hereby declare that the following is a full, clear, and exact description of the invention, which will enable others skilled in the art to 10 which it appertains to make and use the same.

This invention relates to rotary harrows.

The object of my invention is to provide a simple and substantial construction of the harrow-sections as well as the connections 15 therefor, so that the said sections may be easily assembled and firmly connected together.

In the annexed drawings, Figure 1 is a plan view of the harrow, showing my improved 20 construction. Fig. 2 is a perspective view of a section of the harrow. Fig. 3 is a perspective view of a four-armed center piece which forms a very important part of my invention. Fig. 4 is a perspective view of a portion of 25 one of the harrow-sections, showing means of constructing same. Fig. 5 is also a perspective view of a modified form of same. Fig. 6 is a perspective view of the weight attachment, showing two rollers for supporting 30 and carrying same. Fig. 7 is a plan view of means of connecting two harrows together by a rod or beam somewhat forward of the center.

A A represent the four sections of the 35 harrow, which are preferably made of lengths B B, of angle-iron, which are secured at their inner ends to the angle-iron C. The four bars of each section diverge from the center of the harrow and are held in fixed 40 relation to each other by a curved rod or track D, which is secured to each of the bars B by any good means in the position shown. A series of teeth are secured to the bars B in any good manner. A center piece for holding 45 the sections in place when assembled is shown, and consists of a casting having four hollow arms E, and through the center of which is a vertical hole for receiving the king-bolt F, which holds in place the tongue G. 50 Between the two middle bars of each section A is a bar or rod H, which is secured to the

angle-piece C, the outer end of which is secured to a strip I, located somewhat behind the piece C. Each rod H is thus made rigid with its section A, leaving a portion of its 55 forward end projecting beyond the piece C. The curved rod or track D passes over the top of the bars B, projecting somewhat beyond the outside ones, thence turns downward and passes back again under the bars, 60 and terminates at its starting-point, thus forming a loop at either end. A hook D' is hung in one of the loops thus formed, so that each section may be connected up with its 65 neighbor.

In Fig. 3 is shown the center piece, showing the hollow arms, while Fig. 4 shows means of securing the bars B to the angle-pieces C and I, simply using a block J for supporting the bar with a rivet or pin through the whole. 70 Fig. 5 shows also another method of placing and securing the angle-pieces in place. The method of construction, however, I do not of course strictly adhere to. Two arms K are secured to the tongue G, and their outer extremities carry a weight-box L, having a weight M. Beneath each end of the weight-carrier is a roller N, which runs upon the track D. Weights are not new for use on harrows; but heretofore only one roller has 75 been used, and when the weight had reached the connecting-hook between the sections A, as before stated, the weight would overbalance the sections and cause them to tilt up and thus twist the harrow and ending in a 80 breakage or disarrangement of parts, while with the double roller the weight is distributed on the sections, thus holding them down at all times.

In Fig. 7 is shown the method of connecting two harrows together by means of the beam O, which is located forward of the center and allows the harrows to move more freely and naturally than when connected at the center by the king-bolt. As usual, the weights 90 are placed on opposite sides of the harrows in order to cause them to revolve in contrary directions.

It is obvious that more than four sections may be used in constructing this harrow and 95 that various changes may be made, if desired.

In assembling the parts of the harrow it is

only necessary to grasp each section A and insert its bar H into one of the hollow arms E, and after the sections are all placed the hooks D' and the loops of the track D are connected and the device is complete.

Having thus described my invention, what I claim as new, and desire to secure by Letters Patent, is—

1. In a rotary harrow, a center piece comprising a series of radial hollow arms, a tongue pivotally secured to said center piece, a series of harrow-sections of angle-iron, a series of harrow-teeth secured to the said sections, a bar or rod secured to and projecting beyond the inner ends of the sections to engage with the said hollow arms, the track portion secured to each of the sections, means for connecting the sections together at their outer ends, a weight resting on the said track, the arm connected thereto and secured to the tongue, all

arranged substantially as and for the purposes set forth and described.

2. In a rotary harrow the combination of the sections A of angle-iron, the track D secured thereto, the bars or rods H secured between the inner adjacent ends of the bars of said sections, the center portion having the hollow arms E for the entrance of the said rods H, the tongue G pivotally secured to the said center portion, the arms K secured to the tongue, the weight M with its rollers N, to run on said track D and the beam O secured to the tongue all substantially as and for the purposes set forth and described. 25

In testimony whereof I affix my signature 35
in presence of two witnesses.

ROLAND RAKESTRAW.
